ONESIME BOUCHARD, OF SHAWSHEEN VILLAGE, ANDOVER, MASSACHUSETTS, AS-
SIGNOR TO CROMPTON & KNOWLES LOOM WORKS, OF WORCESTER, MASSACHUSETTS,
A CORPORATION OF MASSACHUSETTS.

WEFT-DETECTING MECHANISM.

Application filed October 12, 1923. Serial No. 668,078.

To all whom it may concern:

Be it known that I, ONESIME BOUCHARD, a citizen of the United States, residing at Shawsheen Village, Andover, in the county 5 of Essex and State of Massachusetts, have invented a new and useful Weft-Detecting Mechanism, of which the following is a specification.

This invention relates to weft detecting 10 mechanism of the multiple plunger type, as shown for instance in the prior application of Eppa H. Ryon, Serial No. 509,113, filed October 20, 1921. It has been found that such detecting mechanism is liable to injury 15 when engaged by a misplaced bobbin and it has been heretofore proposed to provide a yielding stand or mounting for the detecting mechanism, by the use of which such injury may be largely avoided. It is the object of my invention to provide an improved 20 construction and arrangement of parts by which the detector stand may be supported for such yielding movement.

A preferred form of my invention is 25 shown in the drawings in which—

Fig. 1 is a side elevation of my improved detecting mechanism, with the shuttle and shuttle boxes shown in section;

Fig. 2 is a front elevation of the parts 30 shown in Fig. 1;

Fig. 3 is a sectional plan view, taken along the line 3—3 in Fig. 1;

Fig. 4 is a sectional rear elevation, taken along the line 4—4 in Fig. 3;

Fig. 5 is a sectional side elevation, taken 35 along the line 5—5 in Fig. 4, and

Fig. 6 is a perspective view of a detail part to be described.

Referring to the drawings, I have shown 40 a portion of a loom frame 10 to which is secured the usual magazine frame 11 on which a weft carrier transerrer 12 is pivoted at 13. A plate or bracket 14 is secured by a bolt 15 to the loom frame 10 and provides 45 a support for the detector stand 16. The stand 16 has a rearward projection 17 which extends through an opening in the bracket 14 and which provides a rear bearing for a plurality of U-shaped detector rods or 50 plungers 18.

A front bearing for the plungers 18 is also provided in the stand 16, as clearly shown in Fig. 5, and the rearwardly extend-

ed short upper ends 18a of the rods or plungers 18 normally extend into the path 55 of a floating lever 19 (Fig. 2) pivotally connected at 20 to the lower end of a link 21, and also pivoted at 22 to an actuating rod 23. The link 21 is connected to suitable mechanism by which substantial exhaustion 60 of weft in the active shuttle may be indicated and a selected fresh weft carrier may be released.

The parts thus far described are in general of the usual type and in themselves form 65 no part of my present invention, which relates particularly to improved means for yieldingly securing the stand 16 to the bracket 14. For this purpose I provide a forwardly extending spring frame 25 (Fig. 70 6), preferably formed of sheet metal with an open central portion and adapted to be secured to the front side of the stand 16 by screws 26 (Fig. 3).

A U-shaped opening 27 (Fig. 6) is formed 75 in the rear plate of the spring frame, which opening is aligned with correspondingly situated openings 28 and 29 in the stand 16 and bracket 14 respectively. A tension spring 30 is secured at its forward end to 80 the spring frame 25 in some convenient manner, as by an eye 31, and is secured at the rear side of the bracket 14 by a cross pin 32.

The openings 27, 28 and 29 are of substantially greater diameter than the spring 85 30 and thus permit free rocking movement of the stand 16 and spring frame 25 in any direction, while remaining effective to return the stand to its seat immediately upon release thereof. The spring frame 25 is 90 preferably formed with a forwardly and upwardly extending flange 33 which forms a stop to limit forward movement of the plungers 18.

The general method of operation of the 95 multiple plunger weft detector is well known and fully described in prior patents and applications. Further description thereof is not believed necessary, as my invention relates specifically to the improved construction by which an elongated tension spring may be used in such a way as to permit free yielding movement of the stand in 100 any direction. It is believed that this is a marked improvement over the constructions 105 heretofore known or used.

Having thus described my invention, what I claim is:—

1. In a weft detecting mechanism, a stand, a fixed frame member by which said stand is supported, and means to yieldingly secure said stand to said member, said means comprising a forwardly extending spring frame mounted on said stand, and a tension spring secured to said spring frame at one end and 10 to said fixed member at the other end and holding said parts in yieldingly contact.
2. In a weft detecting mechanism, a stand, a fixed frame member by which said stand is supported, and means to yieldingly secure 15 said stand to said member, said means comprising a forwardly extending spring frame mounted on said stand and having an open center portion, and a tension spring secured to said spring frame at one end and extending 20 through said open center portion and having its opposite end secured to said fixed frame member.
3. In a weft detecting mechanism, a stand, a fixed frame member by which said stand is 25 supported, and means to yieldingly secure said stand to said member, said means comprising a forwardly extending spring frame mounted on said stand and having an open center portion, and a tension spring secured 30 to said spring frame at one end and extending through said open center portion and having its opposite end extending through aligned openings in said stand and fixed frame member and secured at the rear of 35 said member.
4. As an article of manufacture, a spring frame for a weft detecting mechanism, said frame being formed with an open center portion to receive a tension spring and having 40 means for attaching one end of the spring thereto.
5. In a weft detecting mechanism, a fixed frame, a detector supporting stand mounted in normal fixed position on said frame but 45 movable with respect thereto in vertical and

horizontal planes, a detector slidably mounted in said stand, and resilient means holding said stand and frame in operative relation and having one end anchored with respect to the frame and the other end anchored with 50 respect to the stand, that portion of said resilient means anchored to the stand being free to bend with respect to the portion anchored to the fixed frame.

6. In a weft detecting mechanism, a fixed 55 frame a detector supporting stand mounted in normal fixed position on said frame but movable in vertical and horizontal planes with respect to said frame, a detector slidably mounted in said stand and resilient 60 means passing through said frame and stand and having the ends thereof anchored respectively in the stand and frame, that portion of the resilient means in the stand being capable of lateral movement with respect to that portion lying in the frame. 65

7. In a weft detecting mechanism, a fixed 70 frame, a detector supporting stand mounted in normal fixed position on said frame but movable in vertical and horizontal planes, a detector slidably mounted in said stand, and a spring having one end anchored with respect to the frame and the other end anchored with respect to the stand and passing through 75 said frame and stand.

8. In a weft detecting mechanism, a fixed 80 frame, a detector supporting stand mounted on said frame and movable in vertical and horizontal planes with respect thereto, and resilient means free to bend on its axis supported at the ends respectively by said frame and stand, the portion of said resilient means in said stand being movable to a position out of alignment with the portion in said frame when said stand moves vertically or horizontally with respect to the frame. 85

In testimony whereof I have hereunto affixed my signature.

ONESIME BOUCHARD.
